UNITED STATES PATENT OFFICE.

HENRY H. HINDSHAW, OF ST. PAUL, MINNESOTA.

ROTATING KILN.

Application filed June 24, 1921. Serial No. 480,101.

To all whom it may concern:

Be it known that I, HENRY H. HINDSHAW, a citizen of the United States, residing at St. Paul, in the county of Ramsey and State of Minnesota, have invented certain new and useful Improvements in Rotating Kilns; and I do hereby declare the following to be a full, clear, and exact description of the invention, such as will enable others skilled 10 in the art to which it appertains to make and use the same.

This invention relates to a rotating kiln, and particularly to a kiln of a basic reducing type adapted to heat and reduce certain 15 kinds of ore.

Roasting furnaces which function to add oxygen to the ore are generally known as acid kilns or furnaces and those which extract oxygen are generally referred to as 20 basic kilns.

There exist large quantities of ore bearing rock containing in the aggregate from 25% to 40% of iron and it has been difficult to separate the ore therefrom. The applicant 25 has invented a novel process for separating certain of these low grade ores from the accompanying material by crushing the same and then reducing it at a high temperature without the presence of air, the ore being 30 intimately mixed with some fuel, such as peat.

It is an object of this invention to provide a kiln in which this process can be easily and efficiently carried out, and which kiln is designed 35 to receive the mixed ore and fuel at one end and to discharge the reduced ore and accompanying material at the other end.

It is a further object of the invention to provide such a kiln having means at one end 40 by which the heat is directed into the kiln and having means at the other end for drawing off the products of combustion and also for inducing the heat from the heating means to act upon the material throughout 45 the kiln.

These and other objects and advantages of the invention will become apparent from the following description made in connection with the accompanying drawings, in 50 which like reference characters refer to the same parts throughout the different views, and in which—

Fig. 1 represents a longitudinal central section of the novel kiln; and

Fig. 2 is a transverse section taken on the line 2—2 of Fig. 1.

Referring to the drawings, the kiln comprises a long metal shell 1 lined with the fire brick or other suitable refractory material 2. The ratio of the length of the kiln to the interior diameter is approximately ten to one, the kiln being ordinarily made about sixty feet in length and six feet in diameter. The shell 1 may be suitably reinforced at intervals by the angle members 3 and is supported 60 at spaced points by bearing rings 4 which run upon bearing rollers 5 supported in suitable brackets mounted on spaced piers. The kiln is arranged to have an inclination downwardly toward the discharge end and this 65 inclination is approximately at a slant of one unit drop to fifteen in length. The kiln is provided with a bushing 6 disposed centrally in its upper end, which has flanges thereon engaging the end and projecting 70 slightly therebeyond. The kiln is illustrated 75 as being driven by a gear ring 8 secured thereto, which ring meshes with a gear or pinion 9 which is driven by any suitable or convenient source of power. A fixed feeding tube 7 extends into the bushing 6 and is adapted to be connected with a mixing machine which is a machine of ordinary pug-mill type which thoroughly mixes the ground ore and the fuel. The ore will be forced into 80 tube 7, a portion of a screw conveyor for 85 this purpose being shown in said tube, which conveyor may be driven by any suitable means.

The kiln is shown as open at its lower 90 end and a movable fire brick wall or hood 10 mounted on a truck base 11 is disposed adjacent the end of the kiln. The wall or hood 10 carries a sealing ring 12 into which the lower end of the kiln projects, which 95 ring is omitted for a portion of the extent of the circumference of the kiln at the bottom thereof to form a discharge opening. The fuel nozzle for the burner 13 projects through the wall 10 into the lower end of 100 the kiln and is adapted to burn oil, or gas, powdered coal or other fuel supplied thereto through the pipe connection 14 and to direct the flame into the kiln. The conduit or pipe 14^a is disposed in the top portion of the kiln and is supported at its front end by the tube 7 which is extended at its upper side for this purpose. This pipe is supported at its rear end by the hood 10 which is provided with an opening 110 to accommodate the same. The pipe 14^a is surrounded by another pipe 15 spaced

therefrom, the space between the pipes providing a water jacket, through which water is supplied from the pipe 16, and discharged through the pipe 17. As the wall or hood 5 10 is adapted to be moved away from the kiln, the pipes 14^a and 15 will extend some distance therethrough. A suction fan 18 has its intake pipe connected to the pipe 14^a. The material is shown in the kiln in Fig. 2 15 as *a*, and this material will ordinarily be disposed largely at one side of the kiln and will slide down to maintain practically the same angle as the kiln rotates, the direction of rotation being indicated in this figure by the arrows. The material will discharge at the lower end of the kiln, as indicated in Fig. 1 and will drop into a pit 19 in the bottom of which is shown a conveyor 20 for conveying the same to any 20 desired point.

The operation of the device is as follows:

The ore which has been properly crushed will be mixed with the peat or other fuel material and discharged into the kiln 25 through the tube 7, being forced through this tube to provide an air seal. This ore will be disposed in the kiln, as illustrated in Fig. 2 and will gradually travel downward in the kiln as the same is rotated. The 30 flame and the hot products of combustion from the burner 13 will be directed against the material in the kiln and against the lining of the kiln and the material by contact of said flame and products and by contact with the heated lining will thus be heated to a high temperature. The fuel 35 mixed with the material will burn and as there will be a dearth of oxygen in the kiln the fuel will unite with the oxygen present in the ore and will thus reduce the same. The combustion of the fuel from the burner 40 13, of course, is complete and considerable carbon dioxide will be formed by the combustion. The combustion of the fuel mixed 45 with the ore will not be complete and considerable carbon monoxide will be generated. The fan 18 will be operated and the gas and products of combustion will be drawn through the pipe 14^a at the opening 50 therein near the front end of the kiln. This will cause a draft lengthwise of the kiln at the lower portion thereof and will tend to bring the flames and hot products of combustion into contact with the ore and 55 kiln throughout the length thereof. The material will thus be gradually heated and raised in temperature as it approaches the lower end of the kiln. The gaseous products of combustion will be drawn through 60 the pipe 14^a and fan 18 and these gases containing considerable carbon monoxide, can be burned to generate heat for any desired purpose. The pipe 14 will be kept suitably cooled by the circulation of water through 65 pipes 16 and 17. The gases will follow the

path indicated by the arrows and the pressure in the kiln being slightly below that of the atmosphere, there will be no tendency for the gases to pass out at the lower end with the calcined product.

70

From the above description it is seen that applicant has provided a simple and efficient kiln for reducing the ore without the presence of much free air in contact therewith. The primary object of the operation 75 which is the reduction of a non-magnetic ore to a magnetic ore, thus enabling the ore to be subsequently separated magnetically, being effectively accomplished. The kiln can be made very rugged in structure 80 and has few parts requiring attention for maintenance or operation.

75

It will, of course, be understood that various changes may be made in the form, details and proportions of the apparatus 85 without departing from the scope of applicant's invention, which, generally stated, consists in the matter shown and described and set forth in the appended claims.

85

What is claimed is:

90

1. A reducing kiln comprising a long inclined cylindrical shell for receiving the material, means in one end thereof for directing heat into the kiln, and means adjacent the same end thereof for drawing 95 off the products of combustion from the other end of the kiln.

95

2. A reducing kiln having in combination a long cylindrical shell inclined towards the discharge end, said kiln being 100 open at the discharge end, a sealing wall adjacent the discharge end, a burner projecting into the open end of the kiln for directing heat into the kiln, a conduit extending through the open end of said kiln 105 having an opening at the other end of the kiln, and means for drawing the products of combustion into said conduit and through the same out through the said open end.

100

3. A reducing kiln having in combination a long cylindrical shell inclined towards the discharge end, means for rotating said kiln, means for feeding the material into the upper end of said kiln, said latter end being closed, heating means for the kiln disposed at the lower end thereof, and means for drawing the heating gases and products of combustion from the upper end of the kiln out through the lower end thereof.

115

4. A reducing kiln having in combination a long cylindrical shell inclined toward the discharge end, means through which the material is fed into the upper end of the shell centrally thereof, means for heating 125 the kiln extending into the shell at the lower end thereof, a conduit supported in and adjacent the top of the kiln having an opening near the upper end thereof, means for drawing products of combustion 130

120

125

130

through said conduit, and means for cooling said conduit.

5. A reducing kiln having in combination a cylinder inclined toward the discharge end, the upper end of said cylinder being closed except for a central opening, means through which material is fed through said opening into the upper end of the cylinder said material sealing said opening, the lower end of the cylinder being open, a movable hood disposed adjacent to the lower end of the cylinder having a sealing ring thereon disposed closely adjacent the cylinder throughout the side and upper portions of its circumference, means extending through said wall into the lower end of the cylinder for heating the kiln, and means extending through said hood to the upper end of said cylinder for drawing off the products of combustion from the upper end of the cylinder and out through said hood.
6. A reducing kiln comprising a long cylindrical container, means for supporting and rotating the same in an inclined position, the upper end of the container being closed except for an entrance conduit for the material and the lower end of the cyl-
- inder being open, a member disposed adjacent the lower end of the cylinder to close the same but spaced therefrom at the lower portion to provide a discharge outlet, means carried by said member and extending into the container for heating the material therein, and means extending through said member and into the upper end of the container for drawing off the products of combustion from the upper end of the container through the lower end thereof.
7. A reducing kiln comprising an inclined rotating shell closed at the upper end except for a feeding conduit, means for forcing the material through said conduit to provide an air seal, means extending into the lower end of the shell to heat the same, exhaust means disposed outside of the lower end of the kiln and means connected thereto passing into the kiln and terminating therein adjacent the front end thereof for carrying off the products of combustion from the upper end of the kiln and through the lower end thereof.

In testimony whereof I affix my signature.

HENRY H. HINDSHAW.
